UNITED STATES PATENT OFFICE.

HAROLD D. BREWER, OF OKLAHOMA CITY, OKLAHOMA.

GOLF GAME.

Application filed September 23, 1926. Serial No. 137,352.

This invention relates to games and involves golf principles, the primary object of the invention being to provide a game board representing a golf course, a game piece representing clubs used in the usual golf game, and a puck representing the golf ball.

Another object of the invention is to provide a game piece used in striking the puck wherein the person playing the game may with a degree of accuracy cause the puck to stop at a predetermined position, thereby eliminating, to a great extent, the element of chance.

With the foregoing and other objects in view which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing from the spirit of the invention.

Referring to the drawing:

Figure 1 is a plan view of a game board used in the playing of a game constructed in accordance with the invention.

Figure 2 is a perspective view illustrating the game piece used in connection with the game board and employed for striking the puck.

Figure 3 is a modified form of game piece wherein the support is made to simulate a person.

Referring to the drawing in detail, reference will be had to Figure 1 which illustrates a plan view of a golf course including nine holes, but it is to be understood that the size of the board may be varied to include eighteen holes, without departing from the spirit of the invention.

The reference character 5 indicates generally fairways of a golf course which are extended along the face 6 of the game board in any suitable fashion, the same having a tee 7 at one of the respective ends thereof and a green 8 at the opposite end of each fairway.

The reference character 9 indicates a stream or lake which passes from one end of the game board laterally to cross several of the fairways, the space indicated at 9 constituting a hazard, to the end that should the puck to be hereinafter more fully de-

scribed, stop within the confines of the lines employed in defining the lake or stream, or should the puck have any portion thereof resting in the space, the player will be penalized two strokes, while if the puck lands in the wide portion labeled lake, the player will be penalized three strokes.

The reference characters 10 and 11 indicate bunkers along the fairway which result in a penalty of one stroke to the player should the puck land in one of these spaces.

The game piece forming an important feature of the invention is shown more clearly by Figure 2 of the drawing, and includes a main supporting rod 12 and a base 13 which may be held into engagement with the game board by the fingers of the operator by using the fingers of his left hand in a manner as illustrated by Figure 2.

At the upper end of the rod is a downwardly extended portion 14 to which the tubular flexible member 15 is secured, the same being formed preferably of rubber.

Positioned within one end of the connecting member 15 is a club 16 having the head 17 at its free end, the head being shaped similarly to the shape of a putter used in playing golf.

As illustrated by Figure 3, the supporting portion of the game piece indicated at 18 is in the form of a person, the arms 19 thereof supporting the club 20 which is also connected with the arms and hands through the medium of the tubular flexible member 21.

The reference character 22 indicates the puck used in connection with the game piece, which puck is struck by the club head in playing the game.

In playing the game rules governing the usual golf game are carried out, that is to say the puck is placed on number 1 tee and the player uses the game piece in a manner as illustrated by Figure 2 hitting the puck to drive it along the fairway, the object being to reach the green with as few strokes as possible, it being necessary for the puck to lie within the confines of the circle indicating the green, to consider the puck as holed-out.

Should the puck land in a trap or on the edge thereof, the player is penalized a stroke or number of strokes indicated in the space outlined by the line indicating the bunker or trap.

After the player has reached number 1 green and holed-out, the puck is positioned

on the next tee and the game piece used in the same manner to move the puck along the fairway, or to number 2 green.

I claim:

- 5 A game of the class described, including a game board ruled to simulate a golf course, a game piece including a supporting rod having a base and having its upper end extended downwardly, a tubular flexible member adapted to be positioned over the

downwardly extended end of the supporting rod, a club having a head, said club adapted to be extended into the tubular member to connect the supporting rod and club, and a puck adapted to be hit by the club and 15 moved over the game board.

In testimony that I claim the foregoing as my own, I have hereto affixed my signature.

HAROLD D. BREWER.
